UNITED STATES PATENT OFFICE.

ALEXANDER F. JENKINS, OF BALTIMORE, MARYLAND.

RAZOR-STROPPER.

1,115,824.

Specification of Letters Patent.

Patented Nov. 3, 1914.

Application filed April 5, 1911. Serial No. 619,113.

To all whom it may concern:

Be it known that I, ALEXANDER F. JENKINS, a subject of the King of Great Britain, residing at Baltimore city, State of Maryland, have invented certain new and useful Improvements in Razor-Stroppers, of which the following is a specification.

This invention relates to blade sharpening devices and specifically relates to razor 10 stroppers of that type including a pair of stropping rollers that operate simultaneously on both sides of the razor blade to produce a keen edge.

The invention has for one of its objects 15 to provide a sharpening or stropping device that consists of a pair of stropping rollers located within a housing in the form of a compressible grip that is grasped by one hand and compressed to tension the rollers against the blade with any desired pressure, while the other hand turns the operating crank for the rollers.

Another object of the invention is the provision of an improved housing so 20 conveniently removed for renewal or for substitution of different kinds of rollers.

A further object of the invention is to 25 provide resilient rollers of novel form which allow of an effective stropping contact with the blade.

Another object is the employment of a 30 simple, effective and novel blade holder positioned in the frame or housing of the machine and removably held by yielding catches.

A further object is to provide a pair of 35 compound rollers which have separate stropping and honing surfaces whereby a relatively light compression of the rollers toward each other will cause a stropping action on the blade, and whereby a greater compression will cause a honing action on the blade.

With these objects in view and others, as 40 will appear as the description proceeds, the invention comprises the various novel features of construction and arrangement of parts which will be more fully described 45 hereinafter and set forth with particularity in the claims appended hereto.

In the accompanying drawings, which 50 illustrate one embodiment of the invention, Figure 1 is a perspective view of the blade- 55 sharpening device. Fig. 2 is a transverse section showing the position of the rollers

before the housing or grip is subjected to the pressure of the hand. Fig. 3 is a similar view showing the housing or grip compressed as in use. Fig. 4 is a perspective view of one of the grip members of the housing or casing removed. Fig. 5 is a horizontal section of the device. Fig. 6 is a perspective view of the holder for a "Gillette" blade. Fig. 7 is a plan view of the sharpening device modified for another form of blade. Fig. 8 is a perspective view of a blade holder for the device shown in Fig. 7. Fig. 9 is a plan view partly broken away of one of the combined stropping and honing 70 rollers. Fig. 10 is a plan view partly in section of another form of stropping roller. Fig. 11 is a detail view of one of the retaining catches for the blade holder. Fig. 12 is a detail sectional view of the means for removably holding the handle on the roller shaft. Fig. 13 is a detail sectional view on line *a*—*a*, Fig. 12.

Similar reference characters are employed to designate corresponding parts throughout 80 the views.

Referring to the drawings, the casing or housing A is so proportioned and shaped that it constitutes a grip that can be conveniently embraced by one hand to hold the 85 stropping device, while the operating crank is turned by the other hand. This casing or housing consists of a frame that includes end plates 1, upper connecting bars 2, and a lower connecting bar 3. The upper bars 2 90 are spaced from each other and located at opposite sides of the longitudinal center of the machine and they form pintle rods for the oppositely-disposed approximately semi-cylindrical guards 4 which protect the stropping elements B within the casing, and these guards form movable grip elements that can be compressed toward each other for tensioning the stropping elements B on the blade to be stropped. The upper corners of 100 these grip members 4 or guards are formed with apertured ears 5 through which the rods 2 pass to hingedly connect the grip members with the frame. The end plates 1 are each provided with a pair of arcuate 105 slots 6 that are struck from the rods 2 as centers, and the inner ends of these slots form bearings 7 for the journals formed by the shafts 8 of the rollers B. Into these slots 6 extend arms 9 carried by the ends of the 110 grip members or guards 4, and as a result, when the guards are compressed, the mem-

bers 9 force the elements B together against the opposite sides of the razor blade. If desired, these rollers can be normally held apart by springs 10 fastened at 11 on the inner surfaces of the end plates 1, the extremities of the springs extending upwardly into engagement with the shafts of the rollers, so as to force the latter outwardly.

The guard members 4 are held in proper relation to each other by means of a spring finger 12 fastened to the bottom portion of one guard member and extending therefrom into the other guard member, said finger or spring 12 having a slot 13 into which engages a lug 14 pressed upwardly from the bottom portion of the guard member into which the spring extends. In the same guard member having the lug 14, is struck up another lug 15 with which the curved end 15' of the spring engages, so that when the grip members are pressed together, the spring acting on the lug 15 will be subjected to tension that will cause the grip members or guards 4 to spring apart when the pressure of the hand on the grip members is released. The lug 14, by extending into the slot 13, prevents the grip members from opening or separating beyond a certain point. By pressing the spring 15 inwardly, it can be raised out of engagement with the lug 14 when it is desired to open the housing for any purpose, such as the removal of the rollers or inspection of them.

The advantage of having the rollers normally separated is that the razor blade can be readily inserted between them and adjusted to the proper position and danger of cutting stropping material is avoided.

The rollers B are provided with intermeshing gear wheels 18 so as to rotate simultaneously and one of the rollers has an operating crank 19 that is capable of turning the rollers only in one direction because of the ratchet teeth 20 on the crank engaging teeth 20^a on the shaft of the roller to which the crank is applied. The crank is preferably removable from its shaft for convenience in packing the stropper in a casing, and to permit the crank to be effectively held on the shaft for use, the shaft has a circumferential groove 20^b whereby a shoulder is formed and behind this shoulder engage spring members or jaws 20^c formed by the ends of a spring wire 20^d coiled around the hub of the crank, the gripping portions 20^e of the wire extending through openings 20^f in the hub so as to engage the shoulder formed by the headed end of the shaft. Thus, by a pressure on the crank axially of its shaft, the spring jaws 20^c will yield to permit the crank hub to be applied to or removed from the headed end of the shaft.

The end plates 1 of the grip or housing have sockets 21 that form seats for the blade holder C, the said seats being so positioned

that the razor blade will be disposed tangentially to and between the stropping elements or rollers B. When the holder C and the razor 22 are placed in the machine, as shown in Figs. 1 and 2, the device is gripped by one hand and the guards or grip members 4 are compressed so as to press the stropping elements against the blade, as shown in Fig. 3, and while the device is thus held, the operating handle 19 is turned so as to rotate the rollers B to produce a stropping effect on the edge of the razor blade. It will thus be possible for the operator to regulate the frictional engagement between the rollers and blade by varying the pressure his hand exerts on the yielding members 4 of the grip or housing. As soon as the pressure of the hand is released, the members 4 and stropping elements B move outwardly to normal position and the stropped blade is removed for use.

The razor holder C, Figs. 1, 2 and 7, is designed for use in connection with a "Gillette" blade and consists of two bar-like sections 23, one being provided with studs 24 that pass through openings in the blade, and into openings 25 in the other section of the holder. These two sections have downwardly-extending extremities 26 which enter the seats 21 of the frame A. In order to retain the blade holder in the frame of the device, the extremities 26 on the holder have notches or equivalent means 26^a into which engage the upper free extremities of spring catches 26^b fastened to the end plates of the frame or housing, the said free extremities of the springs extending through openings 26^c in the end plates and being shaped to fit in the recesses 26^a. The springs are of such strength as to retain the holder in place should the device be inverted, but the springs will not interfere with the ready insertion or removal of the blade holder.

For stropping ordinary shank blade razors, the frame A has its rear end plate 27 provided with a slot 27, Fig. 7, which is located in a vertical plane passing centrally between the rollers B, the said slot serving to accommodate the shank of the blade and the sockets or seats 21 are disposed out of line with the slot 27. The razor holder D, shown in Fig. 8, is used for razors of this type, said holder consisting of a bar 28 having a blade-receiving clip or equivalent device 29. The extremities of the bar 28 are offset at 30 and terminate in downwardly-extending members 31 which engage in the seats 21 of the frame A. In the members 31 are screws 32 which engage the bottoms of the seats 21 and determine the position of the edge of the blade with respect to the stropping rollers, and by adjusting the screws, the proper relation between the blade and rollers can be effected.

The sharpening elements or stropping

rollers B may be constructed as shown in Fig. 5, each roller consisting of a soft rubber carrier or body 33 which is formed with a spiral ridge 34, the said ridge having a 5 groove 35 extending the full length thereof to form spaced flanges 36 between which a strip 37 of stropping material, such as leather, is held, the leather being firmly attached to the rubber by cement or the like.

10 The convolutions of the leather strip of one roller are alternated or staggered to the convolutions of the adjacent roller, as clearly shown in Figs. 5 and 7, so that when the rollers are compressed against opposite sides 15 of the blade, one roller will not neutralize the effect of the other.

In order to provide for honing of the blades, the rollers may be constructed as shown in Fig. 9, each roller being provided 20 with a spiral honing surface 38 which is normally below the stropping surface formed by the leather 37, and whenever it is desired to hone the blade, it is merely necessary to compress the grip harder than usual 25 to cause the leather to sink or yield to such an extent that the honing surfaces 38 of the rollers will come into engagement with the razor blade. This effect can be readily accomplished since the body or carrier of 30 the roller is made of rubber, and hence yielding. To increase the yielding of the rubber immediately under the strip of stropping leather 37, grooves 39 may be formed. The rubber of the rollers is molded around 35 the shafts 8 by means of suitable molds, and it is merely necessary, in completing the rollers, to glue the leather strips thereon. Another form of resilient roller is shown in Fig. 10, wherein the resilient carrier consists of a helical spring 40 which has its ends 40 terminating near the axis of the roller and entered in a longitudinal groove 41 in the shaft 8, so that the carrier can be readily removed from the shaft when renewal is 45 required. On this helical spring carrier 40 is cemented a strip of leather 41' for stropping, honing or sharpening the blades.

From the foregoing description, taken in connection with the accompanying drawings, the advantages of the construction and of the method of operation will be readily apparent to those skilled in the art to which the invention appertains, and while I have described the principle of operation of the 50 invention, together with the apparatus which I now consider to be the best embodiment thereof, I desire to have it understood that the apparatus shown is merely illustrative, and that such changes may be made 55 when desired as are within the scope of the claims appended hereto.

Having thus described the invention, what I claim as new, is:—

60 1. A blade sharpening machine comprising a frame shaped to form a grip and hav-

ing an opening, a blade holder removably inserted in the opening, bodily movable rollers arranged to be pressed against the blade, and means for turning the rollers.

2. A blade sharpening machine comprising 70 a pair of sharpening rollers, means for supporting the blade between them, yielding devices at the ends of the rollers for normally holding the latter separated, a support for the rollers, members disposed 75 laterally of the rollers and movably mounted on the support with their ends engaging the rollers for pressing the latter against the blade, and means for turning the rollers.

3. A blade sharpening machine comprising 80 a frame including approximately semi-circular guards forming grip members, a sharpening roller arranged within each guard, means for turning the rollers, and means for holding a blade in co-operative 85 relation with the rollers, said guard members being yieldable toward each other to tension the rollers against the blade.

4. A blade sharpening machine comprising 90 a frame including approximately semi-circular guards forming grip members movably mounted, normally separated rollers mounted in the frame and movable toward each other by compression of the grip members, means for limiting the movement of 95 the grip members and the separation of the rollers, and means for holding a blade in co-operative relation with the rollers.

5. A blade sharpening machine comprising 100 a frame consisting of spaced end walls having slots forming bearings, rollers journaled in the bearings, a guard extending partially around each roller, means on the guards and extending into the slots for removably holding the rollers in the bearings, 105 and means for supporting a blade between the rollers.

6. A blade sharpening machine comprising 110 a frame consisting of spaced end walls having slots forming bearings, rollers journaled in the bearings, a guard extending partially around each roller, means on the guards for removably holding the rollers in the bearings, means for supporting a blade between the rollers, yielding means for 115 spreading the rollers and guards apart, and means for limiting the spreading of the said guards.

7. A blade sharpening machine comprising 120 a frame including end plates having arcuate slots and guards hinged between the end plates on the centers of curvature of the said slots, rollers having journals bearing in the slots, arcuate members on the guards engaging in the slots to retain the 125 journals of the rollers in place, means for turning the rollers, and means for supporting a blade holder in co-operative relation with the rollers.

8. A blade sharpening machine comprising 130

ing a frame including end plates having arcuate slots and guards hinged between the end plates on the centers of curvature of the said slots, rollers having journals bearing in the slots, arcuate members on the guards engaging in the slots to retain the journals of the rollers in place, means for turning the rollers, means for supporting a blade holder in coöperative relation with the rollers, and means for yieldingly separating the rollers to permit the blade to be inserted between them.

9. A blade sharpening machine comprising a frame including oppositely-disposed curved guards movable with respect to each other, a sharpening roller mounted in each guard, a spring member on one guard, and means on the other guard with which the said member releasably engages to hold the guard in position.

10. A blade sharpening machine comprising a frame, sharpening rollers mounted therein, one end of the frame having a slot for receiving the shank of a blade, seats in the ends of the frame disposed out of alignment with the slot, means for turning the rollers, and a blade holder having offset ends engaged in the said seats.

11. A sharpening machine comprising a pair of compressible rollers each having separate surfaces located at different radial distances from the axis of rotation, a holder for supporting a blade in coöperative relation with the rollers, and means for compressing the rollers against the blade for bringing the different surfaces of the rollers into engagement with the blade.

12. A blade sharpening machine comprising a pair of rollers each having separate working surfaces arranged at different distances from the axis of rotation, the higher surface being yieldable to permit the lower surface to be brought to working position, means for supporting a blade between the rollers, and means for compressing the rollers together for engaging the working surfaces thereof with the blade.

13. A blade sharpening machine comprising yielding rollers each having different

working surfaces in the form of helixes of different diameters, means for supporting a blade between the rollers, and a grip for compressing the rollers together to different degrees for bringing the different surfaces of the rollers in engagement with the blade.

14. A blade sharpening machine comprising a pair of rollers each consisting of a yielding carrier having separate working surfaces located at different radial distances from the axis thereof, means for movably supporting the rollers to be compressed toward each other, and means for supporting a blade between the rollers.

15. A blade sharpening machine comprising a compressible grip, a pair of yielding rollers mounted in the grip and movable toward each other by the compression of the grip, each roller having separate working surfaces movable to working position by different degrees of compression of the grip, means for holding the blade between the rollers, and means for turning the rollers.

16. A blade sharpening machine comprising a compressible grip, a pair of yielding rollers mounted in the grip and movable toward each other by the compression of the grip, each roller having separate working surfaces movable to working position by different degrees of compression of the grip, means for holding the blade between the rollers, means for turning the rollers, and means for holding the rollers normally separated.

17. A blade sharpening machine comprising a pair of sharpening elements disposed parallel and rotatably supported, means for holding a blade between the elements, a second means for turning the elements by one hand, and a third means operatively related to the elements and adapted to be actuated by the other hand for pressing the elements and blade together.

In testimony whereof I affix my signature in presence of two witnesses.

ALEXANDER F. JENKINS.
